SEWING MACHINE

Albert H. De Voe, Livingston Manor, N. Y., assignor to The Singer Manufacturing Company, Elizabeth, N. J., a corporation of New Jersey

Application March 18, 1938, Serial No. 196,641

23 Claims. (Cl. 112—197)

This invention relates to sewing machines, more particularly of the two-thread chain-stitch type having a reciprocating eye-pointed needle and a complementary thread-carrying looper.

5 The invention has for an object to provide a machine of this character with mechanism to sever the under or looper thread periodically without stopping the machine, so that the resultant seam will comprise an uninterrupted needle-thread, the work penetrative loops of which are keyed by loops of a looper-thread which is periodically interrupted or severed, resulting in a seam having a series of lengths of looper-thread in end-on relation in the seam.

15 The looper-thread severing mechanism is so contrived as to sever the looper-thread at points such that the last loop of each length of looper-thread of the seam is locked by the finishing end of such length of looper-thread which projects through the needle-thread loop embraced by said last looper-thread loop. Thus each length of looper-thread of the seam is locked against ready ravelling. In the event that ravelling of the looper-thread should occur for any cause, it can 20 only continue for a few stitches or back as far as a point of interruption of the looper-thread. The provision safeguards the entire seam against being readily ravelled.

Another object of the invention is to provide 30 the machine with a simplified and improved looper-mechanism which is capable of extremely high speeds of operation.

Another object of the invention is to provide the machine with a high-speed-responsive 35 thread-controlling mechanism for the looper-thread.

Still another object of the invention is to provide the machine with improved driving mechanism whereby it may be operated at high speeds 40 from the conventional power-transmitters used on the power-tables in garment manufacturing establishments, without the necessity of fitting the driving devices on the power-tables with inordinately large driving pulleys.

45 A still further object of the invention is to provide the machine with a main shaft which is so journaled as to avoid excessive bearing wear caused by the pull of the driving belt which runs from the machine to the usual power-transmitter below the top of the power-table on which the machine is stationed for use.

With the above and other objects in view, as will hereinafter appear, the invention comprises the devices, combinations, and arrangements of 50 parts hereinafter set forth and illustrated in the

accompanying drawings of a preferred embodiment of the invention, from which the several features of the invention and the advantages attained thereby will be readily understood by those skilled in the art.

5 In the accompanying drawings, Fig. 1 is a side elevation of a sewing machine embodying the invention. Fig. 2 is a plan view of the machine bed and mechanism disposed therein. Fig. 3 is a section on the line 3—3, Fig. 2. Fig. 4 is a 10 section on the line 4—4, Fig. 2. Fig. 5 is an end elevation of the clutch-operating means at the left end of the thread-cutter or rear shaft in the machine bed. Fig. 6 is a transverse vertical section through the machine bed adjacent the looper-mechanism. Fig. 7 is a perspective view of the thread-cutter mechanism. Figs. 8, 9, 10 and 11 are perspective views of the needle, looper and thread-cutter implements in their cooperative relationships during a thread-cutting operation. Fig. 12 is a plan view of the looper-actuating mechanism. Figs. 13, 14 and 15 are transverse vertical sections on the lines 13—13, 14—14 and 15—15, Fig. 2, showing the looper-thread take-up, nipper and pull-off devices, respectively. Fig. 16 is a bottom plan view of a portion of the seam produced by the machine. Fig. 17 is a side elevation of the seam. Fig. 18 is a bottom plan view of the seam on a smaller scale than that shown in Fig. 16. Fig. 19 is a section on the line 19—19, Fig. 2. Fig. 20 is a fragmentary plan view of the thread-cutter actuating mechanism in its thrown-out or inactive position. Fig. 21 is a disassembled perspective view of the looper and looper-carrier. Fig. 22 is a plan view of the thread-cutter controlling cam. Fig. 23 is a section on the line 23—23, Fig. 2. Fig. 24 is a perspective view of one of the three similar sleeves carrying the coiled spring shanks of the looper-thread controlling arms shown in Figs. 2, 13, 14 and 15. Fig. 25 is a plan view of the work-feeding mechanism. Fig. 26 is a side elevation of the feed-bar and associated parts below the cloth-plate. Fig. 27 is a perspective view of the feed-bar and feed-dog, and Fig. 28 is a section on the line 28—28, Fig. 26.

40 The machine frame comprises a hollow trough-like bed 1 from a platform or flat surface 2 at one end of which rises the hollow standard 3 of the gooseneck 4 terminating in the head 5 carrying the reciprocating eye-pointed needle 6 which is driven by suitable connections from the upper or needle-driving shaft 7 extending horizontally lengthwise of the overhanging gooseneck 4, being journaled in the bearing bushings 8 and 9 in the gooseneck.

The top or needle-driving shaft 7 is connected by the conventional clip-belt 10 to the main shaft 11 which is journaled in the bushings 12 and 13 in the hollow standard 3 and carries the twin-grooved belt-pulley 14 and balance-wheel 15. It will be observed that, contrary to the usual practice, the belt-pulley 14 is entirely separate from the balance-wheel 15 and is located within the hollow standard 3 between the bearing bushings 12 and 13; the balance-wheel 15, only, being carried by the outboard projection of the main shaft. By these means the strain of the driving belt or belts 16 is applied to the main shaft between its bearings and not to the outboard projection of the main shaft, as heretofore. Longer bearing life and improved operation of the parts are thus attained. The clip-belt 10 runs over the pulleys 17 and 18 on the needle-driving shaft 7 and main shafts 11, respectively; the pulley 18 being double the diameter of the pulley 17, so that the needle-driving shaft 7 runs at twice the speed of the main shaft 11.

Journalized in the bed 1, in parallel relationship below the level of the main shaft 11, are the two bottom shafts 19 and 20 carrying the pulleys 21 and 22, respectively, which are connected by conventional clip-belts 23 and 24 to the respective driving pulleys 25 and 26 on the main shaft 11.

The pulleys 25 and 26 are double the diameter of the pulleys 21 and 22, so that the lower shafts 19 and 20 are each driven at twice the speed of the main shaft 11 or at the same speed as the needle-driving shaft 7.

Cooperating with the needle 6 in the formation of stitches is the thread-carrying looper 27, Fig. 21, the shank 28 of which has a pivot-hole 28' entered by a cross-pin 29 fixed thereto and journaled in bearings 29' in the looper-carrier 30 which rocks on the aligned pins 31 fixed in lugs 32 in the bed 1. The lower shaft 20 carries an eccentric 33 embraced by the follower-sleeve 34 fast on the thin plate-like lever 35 which is supported at its forward end upon the upper end of the upstanding leaf-spring 36 screwed at its lower end to the bed 1. The lever 35 carries at its rearward end the cylindrical actuating pin 37 which enters an actuating hole 38 in the looper-shank 28 offset to one side of the axis of the looper-fulcrum pins 29. The hole 38 is slightly hour-glass shaped, as shown in Fig. 12, to permit freedom of motion of the pin 37 therein, without lost-motion or jamming. Thus, the eccentric 33 and lever 35 impart to the looper 27 its endwise or needle-loop-seizing and -shedding movements.

The usual side-throw movements are imparted to the looper by means of the thin link 39, Fig. 6, which is pivotally connected at its forward end to a bracket 40 having a screw-and-slot adjustable connection 41 with the forward end of the thin lever 35. The link 39 is pivotally connected at its rearward end to the looper-carrier 30 and rocks the latter upon its fulcrum-pins 31. The resultant movement of the looper is the usual elliptical movement commonly performed by thread-carrying loopers in the two-thread chain-stitch sewing machine art. The single eccentric 33 imparts to the looper 27 all of its operative movements through the mechanism described which, it will be observed, is composed of parts which are light in weight and may thus be operated at high speeds.

Mounted on the looper-carrier 30 is the upstanding spring-blade 40 which is arranged to

contact the side of the needle opposite to the side passed by the beak of the looper on its loop-seizing stroke, and prevent the bowing out of the needle-thread on the wrong side of the needle as the latter rises to present its loop for entry by the advancing looper.

The looper-thread cutter comprises a stationary ledger-blade 41 having a shear-cutting edge 42 and a supporting shank 43 which is mounted in the block 44 fixed in the machine bed 1. Co-operating with the ledger-blade is the active blade 45 having a pilot nose 46 and a shear-cutting edge 47 at one side of said nose. The blade 45 is mounted in the grooved head 48 of a vertical rock-shaft 49, Fig. 7, journaled in the vertically spaced arms 50 of the block 44 which carries the ledger-blade 41. Fixed to the rock-shaft 49 is a crank-arm 51 which is connected by the link 52 to the arm 53 of a bell-crank lever 53, 54 fulcrumed on the stud-pin 55 fixed in the block 44. The bell-crank arm 54 is formed with a cam-follower nose 56 which bears upon the cam 57 fast to the worm-gear 58 journaled on the stud-pin 59. A spring-pressed conical plunger-head 60, housed in a hole in the block 44, bears against a shoulder 61 on the lever-arm 54 to hold the nose 56 against the cam 57 at all times.

Meshing with the worm-gear 58 is the worm 62 formed on the sleeve 63 freely mounted upon the shaft 19, see Fig. 4. The sleeve 63 is formed at one end with a collar 64 having a clutch-notch 65 which is entered at times by the clutch-pin 66 secured to the head 67 of a pin 68 which may be slid endwise of and within the hole 69 formed axially of and within the shaft 19. The clutch-pin 66 slides in a hole in a collar 70, Fig. 4, fast on the shaft 19. The slide-pin 68 is formed at its outward free end with a grooved head 71 which receives the forked end 72, 72 of a clutch-controlling lever-arm 73 fulcrumed at 74 in the bed 1. The lever-arm 73 is rigid with the block 75, Fig. 2, having a flat face 76 which is pressed upon by the looped end 77, Fig. 19, of a stiff wire spring 78 slidable endwise in the bed 1 and having at one end an upstanding finger-piece 79 by which it may be manipulated to throw the automatic thread-cutter mechanism into or out of operation.

The wire spring 78 is backed adjacent the block 75 by the flat wall 80 in the bed 1 and, in the position shown in Fig. 2, presses upon the block 75, at the left of the fulcrum 74, thereby urging the slide-pin 68 to the right and causing the clutch-pin 66 to enter the notch 65 in the collar 64 of the worm 62 and couple the worm 62 to the drive-shaft 19. By sliding the finger-piece 79 to the other end of its clearance slot 81 in the bed-plate 82, the looped end 80 of the spring 78 is shifted to the right of the fulcrum 74 of the block 75, or to the position shown in Fig. 20 and the clutch-operating arm 73 is moved in a direction to withdraw the clutch-pin 66 from the notch 65 and disconnect the worm 62 from its drive-shaft. In this position of the parts, the curved free end 83 of the spring 78 rides upon the forwardly offset bed-shoulder 84 and causes the looped end 77 of the spring wire to move the block 75 to the throw-out position shown in Fig. 20.

The cam 57, Fig. 22, has a long concentric portion 85 which holds the thread-cutter blade in retracted position during the sewing of a predetermined number of stitches. At the end of the concentric portion 85 is a slight drop-off 75

shoulder 85' which is timed to allow the thread-cutter to move from the position shown in Fig. 8 to the position shown in Fig. 9 wherein the pilot nose enters the looper-thread loop 86 and detains the latter; the cutting edges 42, 47 remaining open. Following the drop-off shoulder 85' is a short concentric portion 87, Fig. 22, which detains the thread-cutter parts in the partly closed position shown in Fig. 10 until another 10 stitch is made by the needle 6. Following the short concentric cam-portion 87 is a second drop-off shoulder 88 which permits the thread-cutter to move to its fully closed position, Fig. 11, to sever the detained looper-thread loop 86. Following the second drop-off shoulder 88 is the 15 cam rise 89 which opens the thread-cutter blade from the position shown in Fig. 11 to the initial position shown in Fig. 8.

The pivoted block 75 has secured to it a stiff wire arm 90 the free end portion of which is doubled back upon the body of the wire to form a shoulder 91, Fig. 4, and a side face 92, Fig. 2. The thread-cutter actuating lever 54 has a stiff wire extension 93 which terminates in the region 25 of the shoulder 91 and side face 92. The block 75 also has fixed to it a wire brake-arm 94 which, in the thrown-out position of the parts shown in Fig. 20 engages the groove 95 in the collar of the worm 62 and holds the latter from turning 30 with the shaft 19. In this position of the parts, the extension 93 of the lever 54 is locked by the shoulder 91 against movement in a direction to close the thread-cutter blade 45. It will be observed that, in the thrown-in position of the 35 parts, Fig. 2, the shoulder 91 is outside of the range of motion of the free end of the extension 93, so that the lever 54 is free to follow the cam 57. When, however, the cam-follower nose 56 of the lever 54 enters a low point in the cam 57, Fig. 2, the free end of the wire extension 93 of the lever 54 moves in front of the side face 92 of the arm 90 and the clutch-pin 66 cannot be withdrawn by manipulation of the finger-piece 79. It is thus impossible to interrupt the 40 operation of the thread-cutter mechanism with the thread-cutter blade in closed position.

When the finger-piece 79 is in the position shown in Fig. 2, the thread-cutter operates periodically to sever the looper-thread without stopping the machine or interrupting the formation 45 of stitches. The seam produced by the machine under these circumstances comprises a continuous upper or needle-thread 96 formed as usual into a series of loops 97 which penetrate the 50 between substance or material 98 and are keyed by the under or looper thread loops 99 each of which is entered by the next subsequent needle-thread loop 97.

The points 100 of periodical interruption of the 55 looper-thread are so contrived that the last needle-thread loop 97 and looper thread loop 99 prior to each of the points 100 of interruption are keyed by the finishing end 101 of looper-thread, so that the seam is locked by the ends 60 101 of the interrupted looper-thread against ready ravelling.

Should ravelling of the looper-thread occur, for any cause, it may only continue back to a 65 point of interruption of the looper-thread and thus the entire seam is safeguarded against being ravelled out. In the present machine, the looper-thread is interrupted every 17 stitches, but this 70 number of stitches may obviously be varied as desired by re-design of the cam 57 and worm-drive mechanism 58, 62.

The machine is equipped with a suitable work-feeding mechanism. Such feeding mechanism is shown and described in my copending application, Serial No. 196,642, filed herewith and entitled Sewing machine feeding mechanism. The 5 feeding mechanism includes the feed-bar *f*' pivotally connected at its forward end to the upper end of the rocker-arm *f*² on the feed rock-shaft *f*³ to which is fixed the crank-arm *f*⁴ connected by the pitman *f*⁵ to the feed-advance eccentric 10 *f*⁶ on the shaft 20. The eccentric 33 on the shaft 20 is connected by the pitman *f*⁷ to the feed-bar *f*' to impart rising and falling components of motion thereto. The feed-bar has mounted on its overhanging free end the feed-dog *f*⁸ which 15 has a clearance hole *f*⁹ in one side wall *f*¹⁰ for admission of the thread-cutter blade 45 which cooperates with the ledger-blade 41 located directly in front of the short center row *f*¹¹ of feed-dog teeth and between the two spaced side-rows 20 *f*¹² of teeth.

The looper-thread controlling means comprise three independent spring-arms 102, 103, 104 having their spiral spring-shanks 105 coiled about individual sleeves 105' on the arbor-pin 106, Fig. 25 2, fixed in the bed 1 by the set-screw 106'. The free ends 107 of the spring-shanks are anchored in suitable slots 108 in the heads 109 of the sleeves 105' which heads 109 carry set-screws 25 adjustably fixing them to the pin 106. The 30 spring-arm 102, which is the take-up arm, is actuated by the eccentric 110 on the shaft 19 and plays vertically in the slot 111 formed transversely of the block 112 fixed in the bed 1. The block 112 also has a thread-guiding slot 113 35 extending longitudinally thereof and crossing the transverse slot 111. The looper-thread is placed in the slot 113 under the arms 102, 103, 104. The up-and-down motion of the take-up 40 arm controls the slack in the looper-thread; paying out looper-thread to the looper as the latter advances to seize a needle-loop and moves to the extreme of its loop-seizing stroke. The take-up arm 102 also takes up the slack in the looper-thread as the looper retracts from its extreme 45 advanced position to shed the needle-loop. The arm 103, which is operated by the eccentric 103', cooperates with the fixed anvil 114 to clamp the looper-thread during the slack-absorbing action of the take-up arm 103 on the retracting stroke 50 of the looper. The arm 104, operated by the cam or eccentric 104', pulls looper-thread from the supply and later pays it out to the looper through the open nipper 103, 114 during the latter part of the advancing stroke of the looper. 55

The tension of the coil-spring ends 105 of the arms 102, 103, 104 may be adjusted by rotatively adjusting the respective sleeves 105' on the pin 106. The arms 102, 103, 104 are so light in weight that they will easily and quietly follow 60 their actuating eccentrics at speeds of 9000 stitches per minute, at which the present machine has actually been successfully operated.

The block 112 is formed with a seat 115, Fig. 23, which receives the hardened base-plate 116 and the looper-thread tension-plate 117 between which and the base-plate 116 the looper-thread passes. A spring 118 coiled about the stud 119 and backed by the adjusting nut 120 presses the plate 117 yieldingly upon the looper-thread running between the base-plate 116 and the tension-plate 117. 70

The invention is not to be understood as limited to the specific forms and arrangements of parts herein shown and described as illustrative 75

of the invention. Various modifications may obviously be made by those skilled in the art within the spirit and scope of the invention.

Having thus set forth the nature of the invention, what I claim herein is:

- 5 1. A sewing machine having a frame including a bed, a hollow standard rising from said bed, a bracket-arm carried by said standard and overhanging said bed, top and bottom shafts journaled in said bracket-arm and bed, respectively, a main shaft journaled in said standard between the levels of the top and bottom shafts, a power-receiving belt-pulley fast on the main-shaft within said standard, driving connections within said standard between said main-shaft and the top and bottom shafts, and a balance-wheel on said main-shaft outside of said standard.
- 10 2. A sewing machine having a frame including a bed, standard and overhanging bracket-arm, three parallel rotary shafts the top one of which is journaled in said bracket-arm and the bottom two of which are journaled in said bed, a main-shaft journaled in said standard and belt connected to drive said three parallel shafts at twice the speed of said main-shaft, a reciprocating needle actuated by the top shaft, a thread-carrying chain-stitch looper actuated by one of said bottom shafts, and a looper-thread cutter actuated by the other bottom shaft.
- 15 3. A looper mechanism for sewing machines having an actuating shaft, an eccentric thereon, a lever having between its ends a follower portion embracing said eccentric, means to support one end of said lever for movement in a direction toward and from said shaft, a looper-carrier pivotally mounted adjacent the other end of said lever to rock on an axis parallel to the axis of said shaft, a link connected to transmit the endwise movement of said lever to said looper-carrier, a looper having a shank pivotally mounted in said looper-carrier, and means connected to said lever for oscillating said looper upon and relative to said looper-carrier.
- 20 4. In a sewing machine, a looper having a shank formed with a pivot hole and an actuating hole adjacent thereto, a looper-carrier, a pivot-pin passing through said pivot hole and mounted in said looper-carrier, means to rockably support said looper-carrier on an axis transverse to the axis of said pivot-pin, and an eccentric-actuated lever having an actuating pin entering said actuating hole.
- 25 5. In a sewing machine, a looper having a shank formed with a pivot-hole and an actuating hole adjacent thereto, a looper-carrier, a pivot-pin passing through said pivot-hole and mounted in said looper-carrier, means to rockably support said looper-carrier on an axis transverse to the axis of said pivot-pin, an eccentric-actuated lever having an actuating pin entering said actuating hole, and a link-connection with said looper-carrier.
- 30 6. A looper mechanism for sewing machines comprising, a shaft carrying an eccentric, a lever actuated by said eccentric, a support for one end of said lever, a pivotally mounted looper-carrier, a link-connection between said lever and looper-carrier, and a looper pivotally mounted in said looper-carrier and operatively engaged by said lever.
- 35 7. A looper mechanism for sewing machines comprising, a shaft carrying an eccentric, a cylindrical follower embracing said eccentric, a thin plate-like lever carrying said cylindrical follower with the plane of said lever transverse to
- 40 the axis of said follower, a support for one end of said lever, a pivotally mounted looper-carrier, a link-connection between said lever and looper-carrier, and a looper pivotally mounted in said looper-carrier and operatively engaged by the free end of said lever.
- 45 8. In a sewing machine, the combination with a reciprocating thread-carrying needle and complementary under thread mechanism, of means to periodically sever the under thread only without interruption of the stitching function of the machine.
- 50 9. In a sewing machine, the combination with a reciprocating thread-carrying needle and a complementary thread-carrying chain-stitch looper, of means to periodically sever the looper-thread only, without interruption of the stitching functions of the needle and looper.
- 55 10. In a sewing machine, the combination with a thread-carrying reciprocating needle and a thread-carrying looper-blade with means to move the looper-blade endwise into and out of the needle-thread loops and laterally of itself to carry the looper-blade from one side of the needle to the opposite side thereof, of a thread-cutter blade having a pilot-nose and a cutting edge, means to move the pilot-nose of the thread-cutter into a looper-thread loop after the latter has been projected through a needle-thread loop, and means to further move the thread-cutter to sever the looper-thread after the looper has taken the next thread-loop from the needle.
- 60 11. In a sewing machine, the combination with a thread-carrying reciprocating needle and a complementary thread-carrying looper, of a looper-thread cutting implement, a drive-shaft running with the machine, a cam for actuating said thread-cutting implement and manually controlled means to establish and interrupt driving connections between said drive-shaft and said cam.
- 65 12. In a sewing machine, the combination with a thread-carrying reciprocating needle and a thread-carrying looper with means to move the looper endwise into and out of the needle-thread loops and laterally of itself to carry the looper-blade from one side of the needle to the opposite side thereof, of a thread-cutter blade having a pilot-nose and a cutting edge, means to move the thread-cutter blade horizontally over the looper-blade to carry the pilot-nose into a looper-thread loop projected through a needle-thread loop, and means to further move the thread-cutter blade to sever the looper-thread after the looper has taken the next needle-thread loop.
- 70 13. In a sewing machine, the combination with a thread-carrying reciprocating needle and a thread-carrying looper with means to move the looper endwise into and out of the needle-thread loops and laterally of itself to carry the looper from one side of the needle to the opposite side thereof, of a thread-cutter having a pilot-nose and a cutting edge, means to move the thread-cutter horizontally over the looper in the direction of feed of the work to carry the pilot-nose into the looper-thread loop projected through a needle-thread loop, and means to further move the thread-cutter to sever the looper-thread after the looper has taken the next needle-thread loop.
- 75 14. Looper-thread controlling mechanism comprising a shaft having a plurality of eccentrics thereon, an arbor parallel to and spaced from said shaft, a plurality of spring wire arms bear-

5 ing upon said eccentrics and having their shanks anchored to and spirally wound to embrace said arbor, and a looper-thread guiding block having a longitudinal thread-guiding slot and transverse clearance slots into which said arms extend, one of said clearance slots having a bottom wall arranged to coact with its respective arm to periodically nip the looper-thread.

10 15. Looper-thread controlling mechanism comprising a shaft having a plurality of eccentrics thereon, an arbor parallel to and spaced from said shaft, a plurality of spring wire arms bearing upon said eccentrics and having their shanks anchored to and spirally wound to embrace said arbor, a looper-thread guiding block having a longitudinal thread-guiding slot and transverse clearance slots into which said arms extend, one of said slots having a bottom wall arranged to coact with its respective arm to periodically nip the looper-thread, and a manually adjustable 20 looper-thread tension device mounted on said block to tension the thread passing along said thread-guiding slot.

25 16. A thread-controller comprising a shaft carrying an eccentric, an arbor spaced from the axis of said shaft, a spring wire anchored at one end to and coiled about said arbor and bearing upon said eccentric, said wire extending as an arm beyond said eccentric, and thread-guiding means associated with the portion of said wire beyond said eccentric.

30 35 17. Looper-thread controlling means for sewing machines comprising a thread-guiding block having a thread-guiding groove cut longitudinally thereof and a plurality of clearance grooves cut transversely thereof and intersecting the thread-guiding groove, a plurality of thread-controlling members playing in said transversely cut grooves, and means to actuate said thread-controlling members.

40 45 18. Looper-thread controlling means for sewing machines comprising a thread-guiding block having a thread-guiding groove cut longitudinally thereof and a plurality of clearance grooves cut transversely thereof and intersecting the thread-guiding groove, a plurality of thread-controlling members playing in said transversely cut grooves, means to actuate said thread-controlling members, and a manually adjustable spring-

5 pressed thread-tension device mounted on said block and including a pair of tension-plates the dividing plane between which is substantially coincident with the plane of the thread-guiding groove in said block.

19. In a sewing machine, a reciprocatory needle, a complementary looper, a feed-bar, a rotary shaft having an eccentric thereon, and means actuated by said eccentric to impart rising and falling movements to said feed-bar and loop-seizing-and-shedding and needle-avoiding movements to said looper.

10 15 20 25 30 35 40 45 19. The combination with a reciprocatory needle, a thread-carrying looper, and work-feeding mechanism including a feed-dog having spaced side rows of teeth, of a ledger-blade stationarily mounted between said rows of teeth, and a looper-thread cutter blade cooperatively related to said ledger-blade.

21. In a sewing machine, the combination with a feed-dog having an apertured side-wall and spaced side rows of teeth, of a ledger-blade mounted independently of said feed-dog and disposed between said side rows of teeth, and a thread-cutter blade mounted at one side of said feed-dog and extending through the apertured side-wall of said feed-dog into cooperative relation with said ledger-blade.

22. The combination with stitch-forming mechanism comprising a reciprocatory needle and a complementary thread-carrying chain-stitch looper, of means to enter and detain a loop of looper-thread while the needle and looper continue their cooperative stitch-forming functions, and means to sever the detained loop of looper-thread.

23. The combination with work-feeding mechanism and stitch-forming mechanism comprising a reciprocatory needle and a complementary thread-carrying chain-stitch looper, of means to enter and detain a loop of looper-thread while the feeding and stitch-forming mechanisms continue their work-feeding and stitch-forming functions, and means to sever the detained loop of looper-thread after the work has been fed at least one stitch-length subsequently to the detention of said looper-thread loop.

ALBERT H. DE VOE.
